M. McGLAUGHLIN,
WALL-PAPER PASTING AND TRIMMING MACHINE,
APPLICATION FILED MAY 10, 1918.

Patented Mar. 23, 1920.

2 SHEETS—SHEET 2.

UNITED STATES PATENT OFFICE.

MONROE McGLAUGHLIN, OF COLUMBUS, OHIO.

WALL-PAPER PASTING AND TRIMMING MACHINE.

1,334,387.

Specification of Letters Patent. Patented Mar. 23, 1920.

Application filed May 10, 1918. Serial No. 233,711.

To all whom it may concern:

Be it known that I, MONROE McGLAUGHLIN, a citizen of the United States, a resident of Columbus, in the county of Franklin and State of Ohio, have invented new and useful Improvements in Wall-Paper Pasting and Trimming Machines, of which the following is a specification.

This invention has reference to certain new and useful improvements in wall paper pasting and trimming machines, and has for one of its objects to improve the pasting roller by making it hollow to agitate and mix the paste during its rotation, and of a material which will insure the roller holding the paste on its surface, thereby uniformly smearing the same on the paper, and which will not rust or get out of shape when remaining idle in the paste, or not in use.

The invention has for a further object to improve the bearing supports for the trimming roll, whereby the same may be quickly and easily adjusted, to adapt the machine to different thickness of paper as well as unevenness in the paper.

A further object of the invention is to improve the means for regulating the pressure of the wiping brush on the trimming roll, whereby more or less paste may be applied to the paper, without other adjustment.

A further object of the invention is the provision of a cut-off shield and gage, the same coöperating with the trimming roll to prevent the paper, if torn, from becoming entangled about the roll, and that the paper may be easily and conveniently cut at desired points for matching up the paper.

The invention has for a further object, to improve the paper supporting reel or spindle, whereby proper adjustment of the paper thereon may be made for the proper application of paste, and to a new and improved spring tension for the paper supporting reel.

The invention has for a still further object, to improve upon the pressure regulating means for the cutting knives; to a new and improved support for the device, and other and various features of construction hereinafter described and claimed.

In the drawings,

Figure 1 is a plan view of my improved

wall paper pasting and trimming machine, 55 the same being shown attached to a table or suitable support, and parts being broken away to better illustrate the machine;

Fig. 2 is a cross-section through the machine, certain parts shown in an adjusted 60 position, in dotted lines;

Fig. 3 is a detail side elevation, showing one of the side rails of the machine, with certain parts attached thereto;

Fig. 4 is a detail of the paper supporting 65 reel or spindle, broken in two;

Fig. 5 is a detail showing the spring ten- 70 sion for the paper supporting reel, and

Fig. 6 is a detail of the pasting roller.

Like characters of reference denote cor- 70 responding parts throughout the figures.

It is understood that with my machine, 75 wall paper may be simultaneously pasted and trimmed, either along one or both edges, and severed in two parts or strips, if de- sired.

The machine includes a frame 1 and a paste tank 2. The frame is made, preferably rectangular in shape, having the side rails 3 and 4, the front rail 5 and a rear rail 6. The rail 6 has an overlying angular portion 7 adapted to rest on a table or other support 55. The tank 2 is of suitable shape and is adapted to be detachably secured to the frame 1, through hinged catches 8 carried on the front and side walls of the tank 2, adapted to engage lugs 9 secured to the front and side rails 5, 3 and 4 of said frame. All operative parts of the machine are carried on the frame 1, and by detaching the tank it may be easily filled with paste and access had to all operative parts, although to get to and remove such operative parts it is not necessary to remove said frame.

95
The side rails 3 and 4 of the frame are provided with depending hangers 10 having bearings 11. These hangers, when the frame 1 and the tank 2 are assembled, extend down into the tank 2 alongside of the 100 side walls of the tank, and journaled in said bearings 11 are stub shafts of the pasting roller 12. It is understood I may provide the roller 12 with stub shafts at each end, or with one shaft extending through the 105 roller. The roller 12 constitutes one of the important features of the machine.

In all attempts at making pasting and

trimming machines, the pasting roller has been a great source of trouble, and in fact, has prevented the machines from going into universal use. The main reason has been that if made of brass, steel or cast iron, with the exception of brass, they rust, and all being dead and glossy, they would not hold the paste and therefore not a success. Attempts have been made to make the roll of wood, but it dries out, and when hollowed out they warp. Tubular tin rolls have been tried, with a covering of some suitable material, but these have not been a success, because the acid in the paste eats it up and destroys the covering. My pasting roller is made of aluminum and hollow. Being hollow, it agitates and constantly mixes the paste as it revolves, thus keeping the paste always in workable condition. Aluminum is porous and acts more like wood without any of its disadvantages. The surface of the roller is made rough by planing, or by other suitable means. Such a surface will hold the paste and insures the same being uniformly distributed over the surface of the paper and it will not rust. Experience has taught that a pasting roller made of aluminum, with its surface roughened, will do the work, where all others have failed.

Said roller 12 is provided with slightly raised annular portions 13 of suitable width providing frictional contact points for the paper, between the trimming roller and said pasting roller. The drawings do not show the surface of the roller 12, roughened, except the surface of one of the annular portions 13, see Fig. 6. Here the annular portion 13 is shown provided with angularly disposed grooves 13^a, which, in addition to giving a more efficient gripping surface, to provide traction to roll the paper through the machine, also provides for taking up the paste and distributing on the paper at the traction points.

14 designates the trimming roller. This roller has stub shafts or trunnions 15 and 15^a journaled in bearing plates 16 and 17, each of which is pivoted at 18, to a side rail of the frame 1 and provided with an adjusting screw 19 having a threaded connection with a nut 20 on the side rail of the frame. The plate 16 has an opening 21 therethrough, into which may be inserted and have a bearing, a stub shaft or trunnion of the roller 14, and the plate 17 has a curved slot 22 opening out of the upper edge of the plate, into which the short shaft or trunnion 15^a of the roller 14 may be inserted and have a bearing. The roller 14, when in position, is immediately above the roller 12 and co-operates therewith, when paper is fed or drawn through the machine, to receive paste from said roller 12. Adjusting the screws 19 will raise or lower the hinged plates 16 and 17, thereby adjusting

the roller 14 relatively to the roller 12, so as to provide for the passage of very thin or very thick paper between said rollers, and also to take care of any unevenness in the thickness of the paper.

23 designates a cutter supporting shaft. This shaft is preferably square in cross-section, its opposite ends being rounded and having a bearing in the side rails 3 and 4 of the frame. Slidably carried on said shaft 23 are a plurality of collars 24, each collar having a pair of upwardly extended spaced ears 25 and a laterally extended boss 26 provided with a threaded opening therethrough. Pivottally mounted between each pair of ears 25, is an arm 27, and each arm is bifurcated at its forward end between which is journaled a suitable paper cutting disk 28. The rear end of each arm 27 is provided with an enlargement 30 having an opening through which is carried a threaded stem 29, which has a threaded connection with the threads in the opening in the boss 26 on the collar 24. Between the enlargement 30 of each arm 27, and the boss 26 of each collar 24, and on the stem 29, is a coil spring 30^a to provide for flexibility between the cutting disks 28 and the pasting roller 12. The stems 29 above the arms 27 are provided with collars or shoulders 30^b, so that when the stems 29 are screwed down, the ends of the arms 27 on which are journaled the disks 28 will be raised, elevating said disks, the springs 30^a acting to hold the cutting disks 28 in operative position and yielding to permit the disks 28 to rise when necessary to conform to the work. Each stem 29 has a finger-hold portion 31. It is understood, that the collars 24 may be slid along the square shaft 23 to any position, whereby one or both edges of the paper may be trimmed, and if desired, one of the cutters positioned so as to cut the paper into two parts or strips.

The cutter supporting shaft 23 is adapted to be rocked in its bearings for the purpose of raising the cutting disks 28 from the position shown in full lines in Fig. 2 into the position shown in dotted lines in said figure, whereby the trimming roller 14 may be removed from its bearings, or replaced, as the case may be. To rock the shaft 23, I provide levers 32 secured to each end thereof.

Secured to opposite ends of said cutter supporting shaft 23 and located within the frame 1, are plates 35. In these plates are journaled a rod 36 to which is secured a brush 37 made up of a series of bristles secured to the rod and arranged, somewhat in the manner shown in Fig. 1. It is intended that the rod 36 may be rocked in its bearings, so as to adjust the brush 37, which in operative position, wipes the paper passing around the trimming roll 14 so that only a given quantity of paste will remain on the

paper as it passes from said trimming roll, to adjust the rod 36 and the brush 37, I provide an arm 38 secured to one end of said rod and connected with the outer end of said arm is a threaded rod 39, which passes loosely through a boss 40 connected with the plate 35, and having a threaded engagement with said rod 39, and bearing against the boss 40, is a thumb nut 41. It is obvious that upon turning the thumb nut 41, in one direction, the rod 39 will be moved upwardly, oscillating the arm 38 and rocking the rod 36 so as to cause the brush 37 to bear against the paper passing over the trimming roll 14, and if the thumb nut 41 is turned in the other direction, it will move the rod 39 in a direction which will oscillate the arm 38 and lock the rod 36 so as to relieve the pressure of the brush 37 against the paper passing over the trimming roll 14. The thumb nut 41, the threaded rod 39 and the arm connection 38 with the rod 36, may be employed by the operator for adjusting the initial position of the brush 37. Through the agency of the thumb nut 41 and its connections with said rod 36, the operator may adjust the position of the brush 37 at any time, and by means of the levers 32 and pivotal latches 34, he may increase the pressure of the brush against to paper, or release the pressure whereby more or less paste may be wiped off; also place sufficient tension on the cutters 28 to properly trim the paper.

The latches 34 are pivoted on the rails 3 and 4, at 33^a, and each latch has the weighted end 34^b to retain the latches in operative position, their movement in one direction being limited by screws 33 with which they engage. When the levers 32 are depressed and caused to have a locking engagement with the engaging portions of the latches 34, the cutting disks 28 and the brush 37, will be placed in an operative position, see Fig. 2, and will hold the parts in this position; it being assured that the thumb nut 41 has been adjusted so that the brush 37 is bearing against the paper passing around the trimming roll 14 in a manner sufficient to wipe off the excess paste.

To protect the cutter supporting shaft 23, and the supporting and adjusting means for the cutters, from being smeared or becoming clogged with paste during the rotation of the pasting roller 12, which constantly agitates and lifts the paste during its rotation, I provide the guard 41^a, best seen in Fig. 2, which said guard extends across the machine parallel with the roller 12 and above and to one side of the same, and secured at its opposite ends to the plates 35, which in turn are secured to the opposite ends of the cutter shaft 23.

The paper supporting reel or spindle is designated 42, and when in operative po-

sition on the frame, is journaled in the slotted bearings 43 secured or attached to the inside faces of the side rails 3 and 4. The reel is located at the rear of the frame and when the paste tank 2 is connected or attached to the frame 1, the reel as shown, is outside of the tank, or located to the rear of the rear wall of the tank. The reel comprises the spindle 42 and the disks 44 and 45, which are adapted to be screwed on to the opposite threaded ends 46 of said spindle 42; a lock nut 47 being provided for locking the disk 44 in its adjusted position on said spindle 42.

To place a roll of paper on the reel, the disk 45 is removed and the disk 44 adjusted and locked in position. The position of the disk 44 on the spindle 42 will determine whether or not it is desired to trim that edge of the roll, and also whether or not paste will be applied the full width of the roll. After the roll of paper has been placed on the spindle, the disk 45 is screwed on to the spindle so as to confine the roll of paper between the two disks and guide the same through the machine. The paper as it is drawn off of the reel, will pass over a guiding roller 48 journaled on the side rails 3 and 4, at a point preferably just above the edge of the rear wall of the tank 2 so as to protect the paper as it is carried from the reel into the tank. The paper is passed over the pasting roller 12 and around the trimming roller 14, in the manner shown in Fig. 2. A flat spring 49 which is secured to the side rail 3, is adapted to have a bearing against the outside surface of the disk 44 of the reel. This spring will place a tension on the reel and retard its rotation sufficiently to prevent the paper from unwinding, except as it may be drawn through the machine, in the manner explained.

50 designates a cut-off shield and gage. This shield and gage is of approximately the same width as the frame 1, and is pivoted at 51 on the overlying angular portion 7 of the rear rail 6 of the frame, so that said shield and gage may be raised out of position to permit the insertion or removal of the reel for applying a roll of paper thereto, or removing the same therefrom. When in lowered position, the forward edge of the shield and gage 50, rests on the trimming roller 14, so that the paper leaving the trimming roller 14 will pass up over said shield and gage, somewhat in the manner shown in Fig. 2. This shield and gage will protect the paper and prevent the same becoming entangled or passing around the roller in the case that it should become torn or split. The shield and gage 50 is provided with a plurality of cutting edges 52. These cutting edges extend crosswise of the machine and are so spaced that an operator when he desires to sever a pasted strip

from the roll, may run his knife along one of the cutting edges 52, selecting that cutting edge which will enable him to sever the strip with as little waste as possible.

5 These cutting edges may be spaced with a view of permitting the operator to cut a strip from the roll, so as to match up the paper with as little waste as possible, that is to say, where you have a "drop match", 10 after it is ascertained which cutting edge 52 to use in severing the paper, so as to bring about a proper match of the paper, such edge will be used throughout the pasting and cutting operation. The cutting edges 52 are 15 spaced at predetermined distances so as to best adapt the machine to the uses of "drop matching". These cutting edges are further useful where there is no aim to bring about a "drop match" but where in the event 20 the paper is drawn out more than intended, the operator running his knife along one side of the cutting edges best suited for the purpose, thereby obviates unnecessary waste.

For supporting the machine on a table 25 or other support, I provide a bracket 53. This bracket has an arm 54 adapted to engage the under side of the table or support 55, and is further provided with a rest portion 56 upon which rests the tank 2, and 30 somewhat as shown in Fig. 2. The bracket 53 includes a bar 57 adjustably connected with the main portion of the bracket by means of a bolt 58, passing through the bar 57 and through a slot 59 in said bracket. 35 The upper end of the bar 57 is bent and formed with a right-angled portion 60 adapted to be seated in a cut-out portion in the table or support 55, so that its upper face is flush with the upper face of the said 40 table or support. The bar 57 is adjustable on the bracket so as to adapt the bracket to different thicknesses of tables or supports in connection with which it is desired to use the machine.

45 It has been shown and explained, that one end of the shaft of the roller 14 is journaled in a slot 22 opening out of the upper edge of the plate 17. To yieldingly hold this end of the shaft in its bearing, I place 50 on the shaft a sheave wheel 64 around which passes a belt 63, which also passes around an idler pulley 62 connected with one end of a coil spring 61, the opposite end of said spring connected with the table or support 55. To remove the roller 14 the belt 63 is slipped off the sheave wheel 64, as will be 60 understood.

In operation, the shield and gage 50 is 65 swung up out of the way, the reel removed and a roll of paper placed thereon, the disks 44 and 45 adjusted on the spindle of the reel to properly position the roll of paper for pasting and trimming as it is drawn through the machine. The tank 2 is detached and 70 filled with paste and resecured in assem-

bled position on the frame 1. The paper is being threaded through the machine, is passed over the guiding roller 48, over the upper surface of the pasting roller 12, around the trimming roller 14 and over the 70 shield and gage 50. The cutting disks 28 are positioned at suitable points on the cutter supporting shaft 23, according as it may be desired to trim one or both edges of the paper, or for severing a roll into two parts 75 or strips, and one or all of such cutting disks adjusted so as to bear down upon the paper passing over the trimming roll 14, as may be desired.

The brush 37 is adjusted in a position 80 which will wipe off the paper as it comes from the pasting roller, it being obvious that said brush may be adjusted so as to wipe off more or less of the paste, as is desired. As the paper is drawn through the 85 machine and over the pasting roller and beneath the cutters, paste is applied thereto and the paper cut or trimmed. When a strip of suitable length has been drawn from the machine, the operator will, by means of 90 a suitable cutting tool, pass the same over the paper and along one of the cutting edges 52 of the shield and gage, and sever the strip from the roll.

I have described the pasting roller as 95 having a roughened surface, which as stated, facilitates in holding the paste to be applied to the paper and said roller being hollow, the paste is kept in agitation and constantly mixed, and as the paper is drawn 100 over the pasting roller and around the trimming roller, the action of drawing the paper, rotates the trimming roller and the same having frictional engagement with the annular raised portions 13 of the pasting 105 roller, will rotate said roller. The raised portions 13 on the pasting roller are so very slight, that there is not much space, if any, left between the surface of the pasting and trimming roller, and as the trimming roller 110 may be adjusted relatively to the pasting roller, it is obvious that paper of any thickness may be passed between the two rollers and the application of paste to the paper as sured.

115 What I claim is:—

1. In a wall paper pasting machine, in combination, a paste tank, a hollow pasting roller and means for revolvably supporting same in said tank, said roller made of aluminum and having a roughened surface.

2. In a wall paper pasting and trimming machine, in combination, a paste tank, a hollow pasting roller and means for revolvably supporting same in said tank, said roller made of aluminum and having annular raised portions, the surfaces of said raised portions having grooves disposed angularly across such portions, and a trimming roller, said trimming roller and said pasting roller 130

adapted to have frictional contact with the paper at the raised portions on said pasting roller.

3. In a wall paper pasting and trimming machine, in combination with a pasting roller and a trimming roller coöperating therewith, a combined shield and gage, said shield and gage being provided with a plurality of cutting edges.

10. 4. In a wall paper pasting and trimming machine, in combination with a pasting roller and a trimming roller coöperating therewith, a combined shield and gage pivotally mounted on said machine and adapted 15 to rest on said trimming roller, said shield and gage provided with a plurality of predetermined spaced cutting edges extending cross-wise of the machine.

5. In a wall paper pasting and trimming machine, in combination, a pasting roller, a trimming roller coöperating therewith, a cutter shaft adapted to be rocked in its bearings, a lever for rocking said shaft, means adapted to be engaged by said lever for locking said shaft in adjusted position, collars slidably carried on said shaft, arms pivotally connected with said collars, cutting disks revolvably mounted on said arms, means engaging the arms and having a 20 threaded connection with said collars for adjusting the position of the cutting disks, plates connected with the opposite ends of said shaft, a rocking rod journaled in said last mentioned plates, a brush attached to 25 said rocking rod adapted to wipe the paper passing around the trimming roller, and means for adjusting the position of said rocking rod.

6. In a wall paper pasting and trimming machine, in combination, a frame, a paste tank and means for detachably attaching said tank to said frame, a pasting roller and means for revolvably supporting same in said tank, a trimming roller adapted to coöperate with said pasting roller, bearing plates for said trimming roller, said plates pivotally connected to said frame, one of said plates having an opening to receive one end 40 of the shaft of said trimming roller, the 45 other plate having a curved slot into which may be inserted the other end of the shaft of said trimming roller, and means for adjusting the plates, whereby the trimming roller may be adjusted relatively to said 50 pasting roller.

7. In a wall paper pasting and trimming machine, in combination, a frame, a paste tank and means for detachably attaching said tank to said frame, a pasting roller and means for revolvably supporting same in said tank, a trimming roller adapted to coöperate with said pasting roller, bearing plates for said trimming roller, said plates piv-

otally connected to said frame, one of said plates having an opening to receive one end 65 of the shaft of said trimming roller, the other plate having a curved slot into which may be inserted the other end of the shaft of said trimming roller, means for yieldingly holding said shaft in operative position 70 in said slotted bearing, and means for adjusting the plates, whereby the trimming roller may be adjusted relatively to said pasting roller.

8. In a wall paper pasting and trimming machine, in combination with a pasting roller, trimming roller and a cutter or cutters, of a paper reel, said reel comprising a spindle having threaded ends, disks adapted to be screwed onto the threaded ends 80 of said spindle for holding a roll therebetween, and a nut for locking one of said disks in position on said spindle.

9. In a wall paper pasting and trimming machine, in combination with a pasting 85 roller, trimming roller and a cutter or cutters, of a paper reel, said reel comprising a spindle having threaded ends, disks adapted to be screwed onto the threaded ends of said spindle for holding a roll therebetween, a 90 nut for locking one of said disks in position on said spindle, and a spring adapted to bear against the outside face of one of said disks.

10. In a wall paper pasting and trimming 95 machine, in combination, a frame, a paste tank, lugs on said frame and clasps on the tank adapted to engage said lugs for detachably attaching said tank to said frame, a pasting roller revolvably mounted on said frame within said tank, a trimming roller, adjustable bearings for the opposite ends of said trimming roller, a cutter supporting shaft, means for rocking said shaft, means for holding said shaft in adjusted position, 100 cutting disks slidably carried on said shaft, means for adjusting the disks relatively to the trimming roller, a paper reel, and a shield and gage pivotally mounted on said frame, said shield and gage provided with a 110 plurality of cutting edges extending cross-wise of the machine.

11. In a wall paper pasting machine, a pasting roller having spaced annular raised portions, said annular raised portions having 115 angularly disposed grooves therein.

12. In a wall paper pasting machine, in combination, a frame, a trimming roller journaled in said frame, a cut-off shield and gage pivotally connected with said frame, its free edge adapted to rest on said roller, said shield and gage provided with a 120 plurality of spaced cutting edges.

In witness whereof I have hereunto affixed my hand.

MONROE McGLAUGHLIN.
